US00D888888S

(12) **United States Design Patent** (10) **Patent No.:** **US D888,888 S**
Widom et al. (45) **Date of Patent:** **** Jun. 30, 2020**

(54) **AQUEOUS CONTAMINANT REMOVAL DEVICE**

(71) Applicant: **Pool Buddy, LLC**, Bedminster, NJ (US)

(72) Inventors: **David R. Widom**, Winchester, MA (US); **Timothy Jebara**, Far Hills, NJ (US); **Nour Jebara**, New York, NY (US)

(73) Assignee: **Pool Buddy, LLC**, Bedminster, NJ (US)

(**) Term: **15 Years**

(21) Appl. No.: **29/725,329**

(22) Filed: **Feb. 24, 2020**

(51) LOC (12) Cl. **23-01**

(52) U.S. Cl.

USPC **D23/209**

(57) **CLAIM**

The ornamental design for an aqueous contaminant removal device, as shown and described.

DESCRIPTION

FIG. 1 is a top, front, right side perspective view; FIG. 2 is a front elevation view thereof, shown at an enlarged scale;

FIG. 3 is a rear elevation view thereof, shown at an enlarged scale;

FIG. 4 is a left side elevation view thereof;

FIG. 5 is a right side elevation view thereof;

FIG. 6 is a top plan view thereof; and,

FIG. 7 is a bottom plan view thereof.

In the drawings, the broken lines are for the purpose of illustrating environment only, and form no part of the claimed design.

1 Claim, 5 Drawing Sheets
